Design 1: a body size measuring tool is worn on the bottom
half of the body in the same manner as trousers when
measuring the size of the bottom half of the body; Design 1:
the tools are made of an entirely stretch fabric and contain
large circles at the center of a substantially hexagonal region
surrounded by 18 small circles; the parts of the tools on
which the large circles are shown are made of fabric that is
less stretchy than the fabric of the rest of the tools; **1.8** to
